MACHINE FOR FORMING LEADERS

James W. Harvey, Lakeville, Conn.

Application December 2, 1946, Serial No. 713,478

10 Claims. (Cl. 239—2)

1

The operation of knotting or tying together short lengths or strands of gut or synthetic material such as nylon filaments to form leaders has been heretofore done by hand with perhaps only a wire or nail as an abutment or a crochet hook. It has also been customary to employ a chain of operations in order to (1) complete the tying together of several strands to form a leader, (2) straighten the leaders, (3) coil the leaders and (4) place the coils in envelopes and (5) place each envelope in a box. A single leader may consist of from two strands to several strands which may vary from .005" to .025" in diameter. Popular lengths of leaders are 3 foot, 7 foot, 7½ foot, 9 foot and 12 foot, but that is immaterial to my invention. Spanish gut sometimes comes in lengths of 17" and artificial gut, such as nylon, is generally sold in lengths of about 20" for making tapered leaders. It should be understood, however, that so far as my invention is concerned the size and length of strand is immaterial. The tying of the knots by hand is a slow process and on account of the very small sizes of filaments and the very light translucent coloring the operation is extremely trying to the eyes and much time is lost by the necessity for resting the eyes from time to time.

I have accordingly sought to provide mechanism to facilitate the tying of uniform and effective knots and to relieve the operator of the necessity of the previously minute attention required.

I have also sought to ensure proper grading of sizes of the strands of gut, etc. when making tapered leaders.

I have also sought to expedite the work so that a greater quantity can be turned out at less expense.

Accordingly, in the preferred form of mechanism a loop is usually first formed in the usual way on the end of the largest leader section which is then inserted through a hollow tube. I have provided spaced grippers for the strands with an abutment constituting an eye holder between them and twist the filaments between the holder and the grippers so as to form an eye or loop of the twisted strands on the holder between the grippers. The tips of the strands are then disengaged from the grippers and secured to the holder above the eye. The twisted strands are then pulled from the holder. The tips being held by the holder are thus passed through the eye as it leaves the holder. The knot is thus started and is completed by pulling tightly on the two sections of the leader and then clipping the tips at the

2

knot. The leader strands to be used are mounted in tubes across the front of the machine so that they can be graded from the smallest at the tip of the leader to the largest diameter. By arranging these tubes so that they can be slid along from right to left as each size is used I avoid the likelihood of improper grading.

As soon as the leader is complete it is coiled on a reel or drum. When using gut which must be tied while wet I coil the leader under tension on a heated cylindrical drum so that all the kinks are taken out of it while the next leader is being formed. It comes off the drum in a coil all ready to be placed in an envelope and boxed immediately.

Fig. 1 is a front elevation of a machine on which leaders may be formed from strands of gut or artificial strands such as nylon.

Fig. 2 is a plan view of the same.
20 Fig. 2a is a longitudinal section of a modification.

Fig. 3 is an end elevation viewed from the right of Fig. 1.

Fig. 4 is a plan view on a larger scale showing 25 a central abutment and two strand holders with the adjacent ends of two strands to be united as they are held in the machine at the start of operations.

Fig. 5 is a side view showing the strands twisted.
30 Fig. 6 is a side view showing the strands twisted and their ends released from the spaced holders.

Fig. 7 shows the knot started, the tips of the strands being held by the central jaws.

35 Fig. 8 is an enlarged elevation view showing the central abutment with its jaws.

Figs. 9 and 10 show two forms of finished knots.

The holders 10 and 11 are preferably of soft rubber each having slots or slits 12 and 13 for 40 resiliently holding the strands 14 and 15. Strand 14 may be regarded as the first and heaviest strand of a tapered leader. Strand 14 is shown of exaggerated size in order to more readily distinguish it from the next smaller size of strand. 45 Strand 14 is secured in the holders so that its rear end extends an inch or two to the right of holder 11. The front end of the second strand 15 is secured so that its front end extends a little to the left of holder 10. By forming these holders 50 of rubber I am able to hold any size of strand without requiring any adjustment and the strands can be pulled through the holders without injuring the strands.

The central abutment 16 is suitably supported 55 midway of holders 10 and 11 and may be of any

suitable material and has three wires 17, 18 and 19. The two outer wires 18, 19 are resilient and tapered toward the center wire at their tips as shown in Fig. 8 so as to facilitate tucking the ends of the strands between the wire 17 and wires 18, 19 as will be hereinafter explained.

The holders 10 and 11 are mounted in cups 20 and 21 secured on the ends of shafts 22 and 23 which are supported rotatably in the blocks 24 and 25. These shafts have pinions 26 and 27 which are driven from gears 28 and 29 on the counter shaft 30. In order to have one shaft rotate in the opposite direction to the other I employ an idler 31 interposed between one gear and its pinion for instance between gear 29 and pinion 27. The ratio of gear 27 to 29 and 26 to 28 may be conveniently set at 1 to 3 for tying gut and 1 to 4, or vice versa, for tying nylon strands so that a single turn of gear 29 (which has a handle 32) will produce the requisite number of twists in the knot. The gears can be turned by hand or by power if desired.

Shaft 22 is hollow so that a strand can be fed through it and avoid tangling. A hook member 33 may be supported on the end of an arm 34 so that it can slide through shaft 22 to a point accessible near holder 10. Arm 34 is guided in a sleeve 35 and held under bias of a spring 36 against the rubber buffer 37.

At the start of a leader, a loop is tied in any suitable manner on the end of the strand which is to be the line end of the leader. This loop is hooked on to the hook 33 and the arm 34 is pulled to the left by hand thus pulling the first strand length through the hollow shaft 22 but leaving just enough of the strand projecting to the right to enable it to be tucked into the holders 10 and 11 as above described (see Fig. 4).

The front end of the second strand is then tucked into the holders 10 and 11. When the strands are twisted a central eye or loop 16' is thus formed about the central abutment 16. The tips of the strands 14 and 15 are then pulled out of the slots 12, 12 in the holders and pulled down in place between the wire grippers 18, 19 and 17 of Fig. 8 as shown in Fig. 6. The strands 14 and 15 are then slipped out of slots 13, 13 of the holders 10 and 11 and pulled up by hand as shown in Fig. 7, the tips of the strands remaining in the grip of the wire jaws of the abutment. This starts the knot which is completed by pulling the main parts of the strands 14-15 in opposite directions until the tips of the strands are released from the center abutment 16 and the turns of strands are drawn close together. The tips of the strands are then snipped off close to the coil of the knot. By tying the knot in this way both tips come out at the same point as shown in Fig. 9 and can be snipped off simultaneously.

By dividing the central abutment into two parts for holding the tips of the strands separately and drawing one tip upward through the eye 16' formed at the center by the twisting operation while the other is in effect drawn downwardly I can bring the tips of the strands out on opposite sides of the knot if desired as shown in Fig. 10.

By mounting a reel or drum 40 on the end of gear 28 it is possible to coil up the completed leader without moving from the machine.

A coiling drum 40' may be mounted on the hollow shaft 22 as shown in Fig. 2a and in place of the hook 33 for pulling the first strand through the shaft I may provide a funnel 22' which permits the operator to readily insert the first strand from the left toward the right to engage the

holders 10 and 11. The drum 40' may be provided with a hook 33' for the attachment of the loop on the end of the finished leader. By rotating the drum 40' the leader can be quickly coiled upon it.

In making tapered leaders it is highly important that the proper sizes be assembled in proper sequence. As examples, I suggest for a medium heavy trout leader successive sizes of .017", .015", .013", .011" and .009" and for an extra light trout leader .012", .010", .008", .007" and .006". For this reason I provide a series or row of tubular containers 41, 42, 43 etc. for the bundles of strands each being marked with its size e. g. .016, .113, .111 etc. and arrange them in sequence from left to right across the front of the machine where they are slidable in a guide way 44. At the start all the containers are slid to the right and each is moved to the left as its strand is used. When the leader is finished all the containers are moved back to the right.

The vertical containers for the strands may also be carried by a turntable or drum rotatable on a vertical axis beneath the bench on which the tyer is mounted, the front edge of the drum projecting beyond the edge of the bench so that the containers can be brought into an exposed position in sequence. This drum can be driven by the counter shaft.

When handling gut the containers are filled with water as it is necessary to keep the strands wet while tying the knots. After each knot has been tied the last strand is pushed through the tubular shaft—and its rear end tucked into the holders ready to be connected with the next strand and so on till the leader is completed.

As soon as a gut leader is complete it is wound under tension on a drum 40 or 40' which may be heated and left there until set in a coil form. Whereupon it can be immediately tucked in an envelope and placed in a box.

It should also be understood that the heating and coiling of gut leaders may be effected as separate operations.

The machine may be operated by hand as herein shown and described or the gears may be power driven in any suitable manner (not shown) and provided with clutch and control devices so that the rotation may be started by pressing a button or lever and stopped automatically when the desired number of twists have been made.

The two rubber holders are preferably geared together so that they can be driven by one hand as shown or by power—but they could be driven independently.

The rubber holders and the central abutment and wire jaws may also be used without the driving mechanism. In such a case the holders would be held stationary in any suitable base and the abutment inserted between the strands as shown in Fig. 4 and used as a tool for twisting the strands, and then attached to the base while the knot is tied as shown in my Patent No. 2,469,037.

By rotating the holders in the same direction to twist the strands, the barrel knot which is formed will have its coils inclined in opposite directions on opposite sides of the center as shown in Fig. 9. By rotating the holders in opposite directions when twisting the strands the coils will all be inclined in the same direction as shown in Fig. 10. When the tips of both strands are pulled through the central eye in the same direction as shown in Fig. 7 the tips will come out together as shown in Fig. 9. By pulling the tips

75

through the central eye or loop of the strands in opposite directions the tips will come out on opposite sides of the knot as shown in Fig. 10.

I claim:

1. In a leader tyer, two spaced holders having resilient jaws for gripping portions of the ends of leader sections to be joined, means for rotating said holders about a common axis, and a fixed separator holder supported between said jaws having gripping members about which the leader sections are twisted and form an eye and between which members the ends of the leader sections are held while the main parts of the twisted leader sections are drawn over the separator thus passing the free ends through the central eye of the twisted leader sections.

2. In a leader tyer, two spaced soft rubber holders slotted to receive strands to be twisted and an intermediate abutment having means for holding the strands separated to form an eye when the strands are twisted between the holders and having means for gripping the tips of the strands while the twisted strands are pulled from the abutment and the eye of the strands is drawn over the tips to start the knot.

3. In a knot tyer two spaced strand holders each having two resilient jaws to hold short lengths of two strands to be joined, an abutment between said holders with gripping means and means for rotating said strand holders in opposite directions so as to twist the strands about said abutment, and form an eye which can be drawn from said abutment and at the same time draw the tips of the strands through said eye to start a knot.

4. In a leader tyer a pair of spaced holders for holding lengths of strands, an abutment between the holders around which said strands can be twisted, means for creating relative rotation between said abutment and said holders for twisting strands held by said holders, one of said holders having a tubular support and a hook reciprocal through said tubular support for engaging and drawing an end loop of a strand through said support.

5. In a barrel knot tyer, two holders spaced apart from each other and each having two jaws for gripping overlapped strands, a stationary central member between said holders and means for rotating said holders and twisting the strands held by said rotated holders about said central member, said central member having resilient jaws for holding the tips of said strands after the strands have been twisted.

6. In a machine for tying barrel knots, two strand holding devices spaced apart from each other, each device having resilient means for gripping parallel strands to be connected, a rotatable supporting shaft for each gripping device, said shafts being co-axial and arranged in alinement and said means for gripping the parallel strands being offset from the axis of said shafts, a stationary abutment having resilient gripping means mounted between said spaced holding devices and means for rotating said holding devices equally and simultaneously while said abutment is stationary.

7. In a machine for tying barrel knots, two strand holding devices spaced apart from each other, each device having resilient means for gripping parallel strands to be connected by barrel knots, a rotatable supporting shaft for each gripping device, said shafts being arranged in alinement, one of said shafts being hollow to permit passage of strands, an abutment having resilient strand gripping means mounted between said spaced holding devices and means for rotating said holding devices while said abutment is stationary.

8. A barrel knot tyer comprising two spaced pairs of strand holding members, each member having soft rubber strand-engaging jaws, a central stationary abutment member supported between the pairs of strand holding members, said abutment member having means for holding two strands in position spaced apart from each other and means for relatively moving said jaws so as to twist strands held thereby equally on opposite sides of said abutment member.

9. A barrel knot tyer comprising a frame, two pairs of strand-holding relatively rotatable jaws spaced apart from each other, a stationary abutment member supported midway between the pairs of jaws, means for twisting strands equally on opposite sides of said abutment member, said abutment member having means for holding the strands apart while twisting to permit the ends of twisted strands to be passed through between the twisted strands.

10. A barrel knot tyer comprising a stationary abutment member for spacing the ends of two strands to be joined together, means at each side of said abutment member for gripping portions of the two strands to be joined, means for simultaneously rotating said gripping means and twisting said strands equally at each side of said abutment member and forming an eye about the abutment member, said abutment member having jaws for holding the ends of the twisted strands while other portions of the strands are disengaged from the gripping means and pulled away from each other and the twisted portions are stripped from the abutment member and the ends of the strands drawn through the eye of the twisted strands.
